UNITED STATES PATENT OFFICE

JOHN M. ROBB, OF PEORIA, ILLINOIS

STEAM RECUPERATOR

Application filed February 10, 1927. Serial No. 167,123.

My invention relates to a system and means of returning exhaust steam to the boiler through the medium of what I will call a hydraulic fly wheel.

5 One object of my invention is to return the exhaust steam to the boiler under boiler pressure thus saving the amount of heat necessary to convert water into that quantity of steam at that pressure.

10 Another object of my invention is to utilize the difference in weight between a column of water which carries with it a quantity of exhaust steam, and a second column of water only, to assist in the operation of the part of 15 the device which I call the hydraulic fly wheel, and in this connection while water would be the easiest and cheapest medium to use, any relatively non-compressible fluid may be used, such as mercury, though it would be 20 necessary to make a slight difference in the arrangement of some parts of the device to use a fluid which could not be also used in the boiler, though if the boiler and its associated parts are being operated on naphtha, the device 25 may be used as shown equally as well as with water as a fluid.

Other objects of my invention will appear and be described in the specification.

The novelty of my invention will be hereinafter more fully set forth and specifically pointed out in the claims.

In the accompanying drawing I have shown the essential elements of a power plant equipped with my recuperator and all connections necessary for its operation except the appurtenances of the boiler such as the grates and stack.

Referring first to those parts of the drawing which show the ordinary parts of a power plant, and which are shown more or less typically, 1 represents a boiler having a steam and water drum or dome 2 from which a pressure line 3 extends, the latter passing through any suitable superheater 4. The steam is conducted from the superheater 4 through a line 5 to the turbine or engine 6 which may drive a generator or other suitable device 7.

A branch line 8 leads from the steam line 5 to the power side of a boiler feed device 9

and from the delivery side of the latter, feed water is conducted to the boiler through the line 10. The turbine or engine 6 is provided with an exhaust conduit 11 and a branch conduit 12 leads from the boiler feeder 9 to the conduit 11.

These parts constitute the essentials of the usual power plant.

My hydraulic fly wheel consists essentially of the two columns 13 and 14 which are connected together at their upper ends through the medium of the receiver or separator 15, and are also connected together at the bottom by the Venturi or combining tube 16 and circulating pump 17.

The receiver 15 is connected by the pipe line 18 to the steam outlet 3 from the steam dome 2 of the boiler 1, and a branch steam line 19 extends from the steam line 5 to the circulating pump 17, while the exhaust from the latter is conducted through the conduit 20 to the conduit 11, the latter terminating in a nozzle 21 projecting into the Venturi tube 16.

A feed line 22 leads from the column 13 to the suction side of the boiler feeder 9 and in those cases where a fluid is used in the hydraulic fly wheel different from that in the boiler, this feed line 22 would extend upwardly to a water level in the receiver or separator 15 which would then perform, in addition to its functions to be presently described, the further function of separating the fluid used in the boiler from the fluid used in the hydraulic fly wheel.

It is to be understood that proper valves will be provided for controlling the flow of steam through the various lines of the plant.

In those cases where water is used as a fluid throughout the system, the hydraulic fly wheel is filled to a point somewhat above the bottom of the receiver 15, and the boiler is filled to the ordinary level and as steam is generated and the plant set in operation, the exhaust steam from the turbine 6, boiler feeder 9 and circulating pump 17 fills the conduit 11 while the water in the columns 13 and 14 is caused to circulate upwardly through the column 14 to the receiver 15, then down-

wardly through the column 13 and through the Venturi tube 16 where the pressure is converted into velocity and at the proper point in this Venturi tube 16, the discharge of the 5 nozzle 21 is located and the exhaust steam mingles with the water passing through the Venturi tube and is carried with it through the circulating pump 17 and into the column 14 where the velocity is converted into pressure 10 and the exhaust steam travels upward with the water in the column 14 and is discharged into the receiver 15, the steam passing over through the line 18 to the steam line from the boiler while the water passes downward 15 through the column 13 and is again circulated through the device.

It is to be noted that the contents of the column 14 through which the steam and water rise to the receiver 15, is much lighter 20 than the contents of the column 13 so that the greater weight in the column 13 assists the circulating pump 17 in performing its function, and further that the bubbles of steam having a natural tendency to rise in 25 the column 14 still further assist the action of the hydraulic fly wheel.

It is to be noted that in starting the device a quantity of the exhaust steam will be condensed thereby heating the water in 30 the columns 13 and 14 and it is further to be noted that after this water has been heated, condensation will be reduced and the exhaust steam will be restored to the steam line from the boiler though reduced in quantity by the 35 useful work extracted through the turbine or engine and auxiliaries.

It is also to be noted that the hydraulic fly wheel is at all times under boiler pressure through the communication established 40 by the line 18. This pressure serving to compress the exhaust steam and also to increase the pressure at the venturi 16.

Whatever condensation occurs will of course raise the water level in the receiver 45 15 which will correspondingly lower the water level in the boiler the difference being transferred to the boiler through the boiler feed pump 9 and its connections.

By properly insulating the hydraulic fly wheel against heat losses, the heat contained 50 in the exhaust steam as well as a large portion of the steam itself will be returned to the steam line from the boiler and the thermal efficiency of the whole power plant will be greatly increased.

It is to be noted that this system of recovering and recuperating the exhaust steam eliminates the necessity of all forms of condensers with their necessary and incident difficulties 60 and expense of maintenance and further eliminates the necessity for the large quantities of water which must necessarily be available where condensers are used.

Having thus fully described my invention, 65 I claim:

1. In a steam recuperator the combination of a pair of columns, a separator to which both columns are connected, a boiler, means for utilizing the pressure developed by the boiler, a steam line from the boiler to the 70 separator, a Venturi tube between the columns, a circulating pump in the recuperator, and an exhaust steam conduit from the means for utilizing pressure developed by the boiler and terminating in a discharge nozzle associated with the Venturi tube. 75

2. In a steam recuperator the combination of a boiler, means for utilizing the pressure developed by the boiler, a water circulating system connected thereto, means for circulating water in said system, a Venturi tube in said system, and an exhaust steam conduit from the means for utilizing pressure developed by the boiler and terminating in a nozzle associated with the Venturi tube. 80

3. In a steam recuperator the combination of a pair of vertically arranged columns, a separator to which the upper ends of both columns are connected, a boiler, means for utilizing the pressure developed by the boiler, a steam line from the boiler to the separator, a Venturi tube connecting the lower ends of the columns, a circulating pump for circulating water between the two columns to convert the pressure of water in one column to 90 velocity for delivery to the other column to be reconverted to pressure, and an exhaust conduit from the means for utilizing pressure developed by the boiler and terminating in a nozzle associated with the Venturi tube 95 100 whereby exhaust steam will be co-mingled with the water rising in one column thereby assisting the action of the circulating pump.
